UNITED STATES PATENT OFFICE.

OLIVER A. SMITH, OF CLINTON COUNTY, ASSIGNOR OF ONE-HALF TO
WILLIAM F. GANT, OF GRAYSON, MISSOURI.

CULTIVATOR.

SPECIFICATION forming part of Letters Patent No. 494,749, dated April 4, 1893.

Application filed October 15, 1892. Serial No. 448,941. (No model.)

To all whom it may concern:

Be it known that I, OLIVER A. SMITH, of the county of Clinton, State of Missouri, have invented certain new and useful Improvements 5 in Cultivators, of which the following is a full, clear, and exact description, reference being had to the accompanying drawings, forming a part hereof.

My invention relates to improvements in 10 cultivators and consists in the novel arrangement and combination of parts more particularly set forth in the specification and covered by the claims.

In the drawings Figure 1 is a top plan view 15 of my complete invention. Fig. 2 is a side elevation of the same. Fig. 3 is a front elevation in detail showing the supporting frame of the cultivator and the reciprocating bar to which the uprights are attached for supporting and adjusting the beams of the plows. Fig. 4 is a perspective view with parts broken 20 away showing the forward end of the plow beam, means for attaching the same to one of the uprights, and the arch for holding the beam rigidly with the other beam carried by 25 the cultivator. Fig. 5 is a vertical longitudinal section of the gearing and the parts attached thereto for operating the reciprocating bar by hand. Fig. 6 is an enlarged side 30 elevation with parts broken away showing one end of the lever for elevating the rear end of the plow and the collar fixed to the shaft upon which the said lever moves. Fig. 35 7 is a perspective view of the shield and the means for attaching the same to the cultivator; and Fig. 8 is a top plan view of the rear end of the plowbeam and means attached thereto for adjusting and securing the plows to the same.

40 The object of my invention is to dispense with the cumbersome manner of guiding the path of the plows which so far as I am aware is generally done by the feet and substitute therefor a lever which may be actuated by hand from the seat of the cultivator and with but a very little inconvenience on the part of the operator.

45 My invention further consists in means for adjusting the uprights to which the plow beams are secured whereby the same may be 50 set and adjusted to suit the work and it fur-

ther consists in other details more specifically to be referred to hereinafter.

Referring to the drawings, 1 represents a U-shaped bar which forms a support for the 55 remaining parts of the cultivator, and 2 represents a pole which is fastened to the top of the curved portion of the U-shaped bar, the forward end of which pole extends a suitable distance out from the bar 1, the rear end of 60 the same being adapted to support suitable mechanism hereinafter described. To the rear end of the said pole is fixed a keeper 3 as best shown in Fig. 5 through which a square shaft 4 is passed and held in place. The said 65 shaft is of suitable length and extends transversely across the cultivator and is designed to support the several adjustable parts hereinafter described. To the free ends of the said shaft are fixed two plates 5 the said 70 plates extending a suitable distance from the said shaft and supporting a round shaft 6 the length of which corresponds to the square shaft 4. The shaft 6 is supported and held in place by a keeper 7 and support 8 holding 75 the same a suitable distance from the pole 2 and below the shaft 4.

9 represents two collars which are adjustably secured upon the shaft 4 and on which are movably mounted two hand levers 10 having 80 spring pawls 11 attached thereto the engaging ends of which come in contact with the ratchet plates 12 also fixed to the shaft 4 for holding the said levers in any desired position. The pivoted ends of the said levers 85 10 are enlarged and provided with a rounded surface, said surface being grooved to receive a chain 13 one end of which chain is attached to said lever and the opposite end fastened to the plow beam. These levers are intended to 90 elevate the plow and free the same from contact with the earth when occasion arises.

14 represents a reciprocating bar T-shaped in cross section, which is loosely fixed in roller bearings 15 located under the U-shaped 95 bar of the cultivator and fixed thereto by suitable bolts as best shown in Figs. 2 and 3, which allow the said T-shaped bar to be moved laterally for guiding the direction of the plows.

16 represents a plate one end of which is provided with teeth 17 and, interposed be-

tween said plate and the rear end of the pole 2 are three gear wheels 18, 19, and 20 which are loosely mounted upon short shafts or bolts 21 passing through the said pole and through 5 the said plate, the said gear wheels meshing with one another and adapted to impart motion in either direction to the bar 14. To the gear wheel 18 is attached a forked shaped iron 22 which is partially turned by the same 10 and attached to the free end of the said iron are the ends of two chains 23, the opposite ends of said chains being attached to perforated lugs 24, located at the opposite ends of the said bar 14, forming a rigid connection be- 15 tween the gear wheel 18 and the said bar 14. To the gear wheel 22 is fixed a lever 25 carrying a spring pawl 26 the engaging end 27 of which is adapted to be received by the teeth 17 formed on one edge of the plate 16 for 20 holding the said lever in its proper position and further adjusting the bar 14 and holding the same in a rigid position after adjustment is had by the co-operation of the intermediate gear 19. It will be well to state that the spring 25 pawls employed are of well known construction and consequently need no detailed description. To the depending wing 28 of said bar 14 are adjustably secured two hanging supports 29 the lower ends of which are pro- 30 vided with openings for the passage of bolts 30 which bolts extend through the casting 31 forming a movable connection between said casting and supports.

32 represents the plow beams which are of 35 the usual construction one end of which is loosely attached or hinged to the projecting arms 33 forming a part of the casting 31 in a reverse direction to the said casting allowing the said beams to be moved laterally, as best 40 shown in Fig. 4. To the rear ends of the plow beam 32 are attached two castings 34 to which the plow shovels are adjustably secured three of said shovels being attached to one casting in a manner as I shall now proceed to 45 describe.

The outer plow shovels 35 are adjustably secured to two detachable supports 36 one end of which is rounded and adapted to be passed into suitable holes formed on one side 50 of the castings 34 and are held in place by bolts 37. This allows the said shovels 35 to be adjusted independent of the remaining plow shovels. 38 represents two similar supports which are secured to the casting 34 in a similar manner but on the opposite sides of the said castings and are adapted to hold the adjacent or inner shovels 39 in an adjustable position. The intermediate shovels 40 are also adjustable through keepers 41 which are 55 formed by the casting 34 and an additional iron 42 fixed to the said castings as best shown in Fig. 8. Thus it will be seen that the plow shovels may be adjusted in various directions and may be set close together or 60 wide apart as occasion requires. Upon the round shaft 6 are movably secured two braces 43 one end of which is attached to the sup-

ports 29 above the casting 31 which hold the said supports in their proper position when draft is applied to the same, the construction 70 of which I shall now proceed to describe. Each of said braces is composed of two arms 44 one end of which is movably attached to the supports 29 as best seen in Fig. 2.

45 represent clips which are passed around 75 the shaft 6 and having their ends attached to one end of the arms 44. Located between said clips is a roller 46 which bears against the shaft 6 and operates to reduce a certain amount of friction when the uprights 29 are 80 moved in either direction. To the lower ends of the supports 29 are movably attached two draft irons 47 the ends of which are inter- 85 posed between the said lower ends of the supports 29 and the castings 31 to which the plow beams are attached and are held in place by the bolts 30 which also pass through the same.

48 represents a double-tree which is at- 90 tached to the pole 2 forward of the U-shaped bar 1 and to the ends of the said double-tree are attached two bars 49 having a series of openings formed therein for receiving one end of the connecting rod 50 leading from the draft irons 47. By means of the holes formed 95 in the bars 49 the single-trees 51 may be ad- justed in a vertical direction for the purposes well known. 52 represents a shield which may be adjusted in a well known manner and is set to fit on the cultivator no matter 100 what the position of the plows may be.

53 represents an adjustable brace one end of which is attached to the shield 52 and the opposite end is attached to one of the outer shovels 35 as shown in Fig. 1 for supporting 105 the said shield and holding the same in po- sition.

In the drawings I have shown but one shield but in practice I may employ two and attach the additional one to the cultivator in a simi- 110 lar manner. I have also shown means for adjusting the wheels to and from one another upon the square shaft 4 which consists of two arms 54 forming axles for the wheels 55 as shown in Figs. 1 and 2. One end of said arms 115 terminates in collars 55 which encircle the shaft 4 and are movable upon the same, the said collars being held in position by means of nuts 56. Rigidly mounted upon the shaft 4 and between the ends of the U-shaped bar 1 is fixed a support 57 which extends a suit- 120 able distance rearward to which is fixed a seat 58 for the driver. From the foregoing de- 125 scription it will be seen that the operation of the cultivator is accomplished by several le- vers which are located in close proximity to the seat of the driver, the direction of the plows being guided by hand and the rear end of the plow beam or shovel being elevated or lowered in a similar manner.

130 In order to hold the plowbeams at a pre- determined distance apart I employ an arch such as 59 the ends of which are provided with a suitable number of openings 60 on

which arch pins 61 are adjustably secured to the ends of which pins are inserted into holes formed for their reception in the plow beams intermediate of their ends as best shown in Fig. 4.

Attached to the castings 34 are brake pins 62 having curved upper ends which are adapted to receive and come in contact with the levers 10 when the said levers are depressed for elevating the plow shovels.

The general construction of the device may be changed without departing from the nature of my invention particularly the means for holding the shovels to the castings 34, and therefore I do not limit myself to the precise construction herein shown and described.

Having fully described my invention, what I claim is—

1. In a cultivator a shaft 4 attached to the rear end of the pole 2, a second shaft 6 attached to the said shaft 4 by means of plates 5, a U-shaped bar 1 the ends of which are also attached to the said shaft 4, roller bearings attached to the said U-shaped bar at its curved portion, a reciprocating bar held and guided by said bearings, supports 29 adjustable on said reciprocating bar, plow beams attached to the said supports, braces 44 leading from the shaft 6 and connected with said supports, and means for operating the said reciprocating bar by hand, substantially as described.

2. In a cultivator, a reciprocating bar adapted to be operated by hand, plow beams attached to the same and operated thereby, castings 34 attached to the opposite ends of the plow beams, shovels adjustably secured to said castings, levers 10 movably secured to the cultivator and a chain attached to the said lever and the said beams for elevating the same, substantially as described.

3. In a cultivator, gear wheels 18, 19, and 20 movably attached to the same, a plate 16 located above said wheels and having teeth formed thereon, a lever attached to the said wheel 20 for turning the same, a spring pawl 26 carried by the said lever and adapted to engage with the said teeth, a reciprocating bar 14, means for attaching the said bar to the

gear 18, supports attached to the said bar to which one end of the plow beams is attached castings secured to the opposite ends of the said beams, and plow shovels adjustably secured to the said castings, substantially as described.

55

4. A cultivator consisting of a square shaft 4, a pole 2 attached to the said shaft, a round shaft 6 attached to the pole below the same, plates 5 connecting the ends of the said shafts, levers 10 movable upon said shaft 4, means 60 for attaching the said levers to the plow beams, a U-shaped bar 1 attached to the said pole and to the shaft 4, a reciprocating bar 14 movably secured to the bar 1, supports 29 adjustable on said bar 14, castings 31 hinged to the lower end of said supports and uniting the ends of the plow beam, castings attached to the opposite ends of the said beams, plow shovels adjustably secured to the said castings, and means attached to said bar 14 for 70 operating the same by hand, substantially as set forth.

5. A cultivator consisting of shafts 4 and 6 attached to the pole 2 below the same, levers 10 movable upon said shaft 4, means for attaching the said levers to the plow beams, a U-shaped bar 1 fixed to the pole 2 and the shaft 4, bearings 15 attached to the said bar 1, a reciprocating bar 14 movable within said bearings, supports 29 adjustable on said bar 80 and to which one end of the plow beams is attached, gear wheels 18, 19, and 20 movably mounted upon said pole 2, shafts 21 passing through the same, and through the said pole, a plate 16 fixed to the upper end of said shafts, 85 teeth 17 formed in the said plate, a lever 25 attached to the wheel 20, a spring pawl 26 carried by said lever and adapted to engage with said teeth, a forked shaped iron 22 fixed to the wheel 18, and chains 23 attached to the 90 said iron 22 and to the ends of the said reciprocating bar 14, substantially as described.

In testimony whereof I affix my signature in the presence of two witnesses.

OLIVER A. SMITH.
